(57) **CLAIM**

The ornamental design for an exhaust pipe for a vehicle, as shown and described.

DESCRIPTION

FIG. 1 is a perspective view of a first embodiment of an exhaust pipe for a vehicle according to my new design;

FIG. 2 is a front view thereof;

FIG. 3 is a side view thereof.

FIG. 4 is a perspective view of a second embodiment of the exhaust pipe for a vehicle according to my new design;

FIG. 5 is a front view thereof; and,

FIG. 6 is a side view thereof.

The broken lines are for illustrative purposes only and form no part of the claimed design.
